UNITED STATES PATENT OFFICE.

ERNEST G. SCHREYER AND CHARLES HEWSON, OF CHICAGO, ILLINOIS.

TOY.

1,408,037.

Specification of Letters Patent. Patented Feb. 28, 1922.

Application filed October 27, 1920. Serial No. 419,792.

To all whom it may concern:

Be it known that we, ERNEST G. SCHREYER and CHARLES HEWSON, both citizens of the United States, and residents of Chicago, in 5 the county of Cook and State of Illinois, have invented certain new and useful Improvements in Toys, of which the following is a specification.

This invention relates in general to toys, 10 and has more particular reference to that type in which an object is projected from a box or cabinet upon release of the cover.

One of the novel characteristics of our invention resides in the provision of a cabinet 15 which is preferably constructed to resemble a miniature phonograph provided with a handle or crank such as is customarily employed in winding up a phonograph, and upon the inside of the cabinet is mounted 20 a suitable mechanism operated by the crank by which the cover may be released so as to permit the forcible projection from the cabinet of some object which will, to the surprise of the person to whom the toy is 25 handed, appear upon manipulation of the crank instead of a musical reproduction which would naturally be expected, from the appearance of the toy.

In order to facilitate an understanding 30 of our invention, we have illustrated on the accompanying drawing a preferred embodiment thereof, from an inspection of which, when considered in connection with the following description, the invention and many 35 of its desirable attributes should be readily appreciated.

Referring to the drawings:

Fig. 1 is a vertical sectional view through 40 a toy embodying our invention;

Fig. 2 is a sectional view on the line 2—2 of Fig. 1; and

Fig. 3 is a transverse sectional view on the line 3—3 of Fig. 1.

By reference to the drawings, it will be 45 observed that the cabinet, which is preferably made of sheet metal, is made in semblance of a miniature phonograph and comprises the body portion 4 supported upon the legs 5 and provided with a cover 6 hinged 50 at 7 and normally urged into open position by a spring 8 coiled about the hinge pin 7 with one end resting against the inner surface of the cabinet body, and the other end against the inner surface of the cover, as 55 shown in Fig. 1. The position that the cover will assume under the influence of the

spring 8 when released is shown in dotted lines in Fig. 1.

Beneath the cover within the cabinet, there is hinged upon a transverse rod 9 a 60 plate or shelf 11, which is also urged into the upright position shown in dotted lines in Fig. 1 by a spring 12 coiled about the rod 9, one end of the spring engaging the forward wall of the cabinet and the other 65 end engaging beneath the plate 11, as will be apparent from the drawings.

Upon the plate 11, there is disposed any suitable object 13, such as a collapsible figure, for instance, or any other relatively 70 light object which, when the cover is released so that it assumes its open position, will be projected upwardly from the cabinet by the plate 11, as the plate rapidly moves under the influence of the spring 12 from the full 75 line to the dotted line position shown in Fig. 1.

The cover is adapted to be locked in closed position by a pivoted latch 14 fulcrumed at 15 upon the front wall of the 80 cabinet, the upper end of the latch being formed to provide a hook 16 adapted to engage an eye 17 secured to the interior of the cover. The lower end or tail of the latch is bent to provide a loop 17, by which the 85 latch is swung on its pivot through the instrumentality of a member 18 slidably mounted upon a transversely extending rod 19 and having one arm 21 engaged with the loop 17, and the other arm 22, which projects upwardly, engaged with a convolution of a spiral 23 preferably formed of wire and rotatably mounted at its ends in the side walls of the cabinet so that the axis of the spiral is disposed in substantial parallelism 90 with the rod 19. One end of the spiral is equipped with a crank 24, which is disposed outside the cabinet substantially in the location of the usual crank by which a phonograph is wound up.

It will be apparent that when the crank is turned in a clockwise direction viewing Fig. 3, the member 18 will be moved along the rod 19 to the right, viewing Fig. 2, thereby swinging the latch 14 upon its fulcrum to 100 release the hook 16 from the eye 17 and that upon rotation of the crank in a reverse direction, the latch will be swung in the opposite direction to re-engage the hook 16 with the eye 17.

In the operation of our toy, the plate 11 is first depressed into the cabinet, then the ob-

100

105

110

ject 13 to be projected is positioned thereon, whereupon the cover 6 is swung to closed position and there held until by manipulation of the crank 24 in a reverse direction the 5 hook 16 of the latch is engaged with the eye 17' to lock the cover in closed position. With the various parts thus positioned and locked, the toy may be handed to one unfamiliar with its workings with the information that 10 by winding up the machine, a musical reproduction will be produced. The victim in anticipation of a selection will unsuspectingly turn the crank in the customary direction, whereupon after a few turns the latch 15 being released from the cover eye 17' by the rotation of the crank, the cover will fly open and the object 13 will be projected upwardly from the cabinet toward the unsuspecting manipulator of the crank to the amusement 20 of the bystanders.

It is believed that our invention and its mode of operation will be understood from the foregoing without further description and it should be obvious that the details of 25 construction are capable of considerable modification within the scope of the invention as defined in the following claims.

We claim:

1. A toy, comprising a cabinet, a cover 30 therefor, a latch for securing said cover in closed position, means including a rotatable crank for locking and releasing said latch, and means for automatically projecting an object from said cabinet upon release of said 35 cover.

2. A toy, comprising a cabinet, a hinged cover therefor, a latch for locking said cover in closed position, means for projecting an object outwardly from said cabinet upon

release of said latch, and means for operating 40 said latch, including a rotatably mounted spiral, a crank for rotating said spiral, and a member connected to said latch and adapted to be moved by said spiral.

3. A toy, comprising a cabinet, a cover 45 therefor, a latch for securing said cover in closed position, a rotatably mounted spiral, an operating crank therefor outside said cabinet, and means actuated by said spiral for moving said latch into operative and in- 50 operative positions.

4. A toy, comprising a cabinet, a hinged cover therefor, a pivotally mounted latch, a rotatably mounted spiral disposed within said cabinet, a crank therefor outside the 55 cabinet, and a slidably mounted member connected with said spiral and with said latch, said member being adapted to swing said latch on its pivot into operative or inoperative position upon rotation of said spiral in 60 one direction or the other.

5. A toy, comprising a cabinet, a hinged cover therefor, a pivotally mounted latch, a rotatable spiral within the cabinet, a manually operable crank disposed outside the cabinet and connected to said spiral whereby the same may be rotated, a rod extending 65 transversely of said cabinet in parallelism with said spiral, and a member slidably mounted upon said rod and affording a connection between said spiral and said latch whereby said latch is swung about its pivot into operative or inoperative position upon rotation of said spiral in one direction or the 70 other.

ERNEST G. SCHREYER.
CHARLES HEWSON.
